SHOE LACE FASTENER

Eldon C. Henderson, Paso Robles, Calif.

Application November 1, 1956, Serial No. 43,620

Term of patent 14 years

(Cl. D17—1)

FIG. 1

The broken line showing of shoe laces is for illustrative purpose only.

I claim:

The ornamental design for a shoe lace fastener, as shown and described.
